(57) **CLAIM**

The ornamental design for tool for chip removing machining, as shown and described.

DESCRIPTION

FIG. 1 shows a perspective front view of a tool for chip removing machining.

FIG. 2 shows a side view of the tool of FIG. 1.

FIG. 3 shows another side view of the tool of FIG. 1.

FIG. 4 shows another side view of the tool of FIG. 1.

FIG. 5 shows another side view of the tool of FIG. 1.

FIG. 6 shows a rear view of the tool of FIG. 1.

FIG. 7 shows a front view of the tool of FIG. 1.

FIG. 8 shows a perspective front view of a tool for chip removing machining of a second embodiment.

FIG. 9 shows a side view of the tool of FIG. 8.

FIG. 10 shows another side view of the tool of FIG. 8.

FIG. 11 shows another side view of the tool of FIG. 8.

FIG. 12 shows another side view of the tool of FIG. 8.

FIG. 13 shows a rear view of the tool of FIG. 8; and,

FIG. 14 shows a front view of the tool of FIG. 8.
